UNITED STATES PATENT OFFICE

147,252

DESIGN FOR A REFRIGERATOR

Florence P. Rothert, Inglewood, Calif.

Application December 15, 1945, Serial No. 124,785

Term of patent 14 years

(Cl. D67—3)

To all whom it may concern:

Be it known that I, Florence P. Rothert, a citizen of the United States, residing at Inglewood, Los Angeles County, California, have invented a new, original, and ornamental Design for a Refrigerator, of which the following is a specification, reference being had to the accompanying drawing, forming a part thereof.

Fig. 1 is a perspective view of a refrigerator showing my new design in open position;

Fig. 2 is a front view thereof in closed position; and

Fig. 3 is a side view thereof in open position.

The dominant features of the design reside in the portions shown in full lines.

I claim:

The ornamental design for a refrigerator, substantially as shown and described.

FLORENCE P. ROTHERT.
